UNITED STATES PATENT OFFICE.

ABRAHAM GOLDBERG, OF NEW YORK, N. Y.

GARMENT.

1,013,764.

Specification of Letters Patent.

Patented Jan. 2, 1912.

Application filed July 26, 1911. Serial No. 640,573.

To all whom it may concern:

Be it known that I, ABRAHAM GOLDBERG, a citizen of the United States, and a resident of the city of New York, borough of Manhattan, in the county and State of New York, have invented a new and Improved Garment, of which the following is a full, clear, and exact description.

This invention relates to garments such as suits, dresses and the like, for use by school children, saleswomen and others, and has reference more particularly to a garment which comprises a body having associated therewith a movable flap, and a pocket normally concealed by said flap, said flap being movable into a position to render said pocket available for use, and means for holding said flap in said last-mentioned position.

20 The object of the invention is to provide a simple, strong and durable garment of any desired style, size, shape or form, which can be used by school children, saleswomen or others, who, at certain times require the use of pockets or the like which at other times are not needed, in which these pockets or other receptacles can be concealed when not in use, in which the means for concealing the pockets simulate 25 in appearance a part of the garment body and may harmonize with the same in form and ornamentation, and in which the general appearance or style of the garment is not affected by the special device of my 30 invention.

The invention consists in the construction and combination of parts to be more fully described hereinafter and particularly set forth in the claims.

40 Reference is to be had to the accompanying drawings forming a part of this specification, in which similar characters of reference indicate corresponding parts in all the views, and in which—

45 Figure 1 is a front elevation of a school dress for use by girls, constituting an embodiment of my invention and showing the special pocket concealed; Fig. 2 is a similar view showing the flap in position to render 50 the pockets available for use; Fig. 3 is an enlarged, vertical section on the line 3—3 of Fig. 2; and Figs. 4 and 5 are similar views of a modified form of my invention.

55 Before proceeding to a more detailed explanation of my invention, it should be clearly understood that notwithstanding

that the same is particularly useful in connection with garments to be worn by school children, it can also be advantageously applied to other forms of garments, for example to work-dresses used by saleswomen, operatives in factories, etc. In the case of school children for example, it is desirable to provide their garments with a number of pockets which are to be used particularly 60 while the children are at school. These pockets may be used for different purposes, for example as containers for pencils, slate rags, or other implements. At other times these pockets are not necessary and would 70 tend to render the garment unsightly. My invention therefore provides means for concealing these pockets, when they are not in use.

Certain of the details of construction 75 shown for example herewith, form no part of the invention and can be varied in accordance with individual preference and special conditions, without deviating from the essence of the invention as defined in the 80 appended claims.

Referring more particularly to the drawings, I have shown for example, a dress fashioned from any suitable material, having a waist portion 10, a skirt 11, and sleeves 12. 85 I designate the waist portion and the skirt portion together, as the body of the garment. These two parts of the garment as separated by a belt 13 of any suitable form having at the front a removable section 14 secured in place at its extremities by means of buttons 15. Extending downwardly from the waist of the garment body and beginning under the belt section 14 is a normally 90 depending flap or panel 16 of suitable form, and preferably extending to the lower edge of the skirt, where it can be secured in position by means of buttons 17 or any other suitable fastening. I prefer to construct 95 the flap or panel so that it resembles in appearance and simulates some part of the body of the garment, for example some portion of the skirt, which may be constructed so that it, too, has the appearance of ornamental panels.

At the under side I provide the flap with 100 a plurality of pockets 18 of different shapes and sizes, and designed for different purposes. When the flap is raised, as shown in Fig. 2, the pockets become available for use. 110 At the same time additional pockets 19 and 20 secured to the skirt at the front thereof

and normally concealed by the flap, also become available for use. I provide buttons or other fasteners 21 for securing the flap in the raised position. The belt section 14 can be loosened at one end or the other when the flap is being raised, and can subsequently be again buttoned over the flap to render more pleasing the appearance of the garment.

Referring more particularly to Figs. 4 and 5, the modified form of my invention there shown has a garment body comprising a waist portion 22, a skirt 23, and a belt or waistband 24. At the waistband is secured a normally depending flap 25 which, when in its lowered position, extends through a slit or opening 26 at the waist of the garment, to the inside of the skirt, so that it can depend at the inside in a concealed position. When it is desired to use the pocket 27 carried by the flap it is drawn out through the slit 26 and secured in a raised position by means of the buttons 28 or any other suitable fasteners.

Having thus described my invention, I claim as new, and desire to secure by Letters Patent:

1. A dress comprising a waist and a skirt, a normally depending flap secured at one

end thereof to the dress near the waist-line thereof, and means for securing said flap in a depending position and in a raised position, the dress having a pocket concealed by said flap when in a depending position, said pocket being uncovered and being available for use when in its raised position, said flap when in its depending position coinciding with the adjacent portion of the skirt, whereby it will simulate a part of the skirt.

2. A dress comprising a waist, a skirt, and a belt at the waist-line thereof, said belt having a removable part, a flap secured at one end thereof to the dress under the removable part of said belt and adapted to be arranged in two positions, and means for securing said flap in its different positions, said dress having a pocket normally concealed by said flap, said flap when in its depending position coinciding with the adjacent portion of the skirt.

In testimony whereof I have signed my name to this specification in the presence of two subscribing witnesses.

ABRAHAM GOLDBERG.
